RADIO STAGE FOUNDATION

Dwight V. Sinninger, Chicago, Ill., assignor to
 Johnson Laboratories, Inc., Chicago, Ill., a corporation of Illinois

Application February 25, 1939, Serial No. 258,560

5 Claims. (Cl. 173—328)

My invention pertains to stage foundations for radio purposes and tube sockets adapted therefor, by which the sockets combined with metal mounting plates and improved capacitor plates forming a part of the invention, provide compact, effective and versatile stage foundations, containing in most compact form not only insulating supports for the tubes employed and connection clips for separable engagement with the prongs of the tubes, but also closely associated by-pass capacitors, as well as connection plates, without the use of connecting wires and without changing in any way the construction of the sockets or capacitor plates, since the latter are so made as to be capable of assembly in the stage foundation units, in many relations without structural change of any kind, to take care of a large number of different circuit hook-ups.

The improved stage foundation described is particularly adapted for use with thermionic tubes of acorn type, and particularly advantageous for ultra high frequencies, for example, frequencies of 50 megacycles and higher.

The socket portion of the stage foundation is made preferably of ceramic material, although other materials such phenyl condensation products and resins either natural or synthetic may also be used, and in fact any material may be used that is susceptible of being molded or formed in the shape described and which has the electrical properties requisite for successful operation under the particular conditions in any case.

The invention also includes a novel construction of socket clip for separable engagement with a terminal prong of the tube, by which the prong is invariably positively but at the same time yieldingly engaged by the clip when a tube is in place in the socket by rotary movement of the tube, which clip construction at the same time provides for said positive engagement even when the terminal prongs of the tubes are out of proper position either axially or angularly relatively to the rotary movement of the tubes, which is frequently the case particularly with small tubes of the acorn type having terminal prongs extending radially from the body portions of the tubes. Furthermore, by the invention the conductive path through the socket clip is maintained substantially constant, whether the prong engagement therewith is normal or is displaced either axially or angularly of the tube from its normal position, said conductive path invariably being the shortest and most direct path possible from the position of prong engagement therewith

to the hook-up conductor connected with the clip.

The above and other objects and advantages of my invention will more clearly appear in connection with the several drawings illustrating a preferred embodiment of my invention, as follows:

Fig. 1 is a plan view of the socket portion of my stage foundation, to an enlarged scale,

10 Fig. 2 is a bottom view of the structure shown in Fig. 1,

Fig. 3 is a vertical, sectional view of the structure shown in Fig. 1, taken along the line 3—3,

15 Fig. 4 is a plan view of the socket illustrated in Figs. 1, 2 and 3, equipped with contact clips and in place on a mounting plate to constitute my improved stage foundation,

Fig. 5 is a plan view of one of the capacitor plates constituting a part of my stage foundation,

20 Fig. 6 is a side view of the capacitor plate shown in Fig. 5,

Fig. 7 is a schematic circuit drawing illustrating one use of my improved stage foundation,

25 Fig. 8 shows in plan view a second capacitor plate of the construction shown in Fig. 5, but in the position in which it is assembled to constitute a part of the stage foundation illustrated in Fig. 4,

30 Figs. 9, 10 and 11 are respectively vertical, sectional views through the stage foundation taken along lines 9—9, 10—10 and 11—11 in Fig. 4,

Fig. 12, 13, 14 and 15 are respectively a plan view, a left-hand side view, a right-hand side view, and a lower end view to a further enlarged scale of one of the connection clips used as a part of the socket,

35 Figs. 16 and 17 show in views similar to Fig. 15, one of the connection clips with a tube prong in its position of entry and in its position of normal engagement with the connection clip respectively, and

40 Figs. 18 and 19 show respectively in views similar to Fig. 13, the engagement of one of the connection clips by a tube prong that is in lower than normal position in Fig. 18 and higher than normal position in Fig. 19.

45 Similar numerals refer to similar parts throughout the several views.

50 As shown in Figs. 1-3 inclusive, I illustrate the flat insulating base 10 of my socket construction as provided with a central clearance aperture 11 for clearing the mid-portion of the body of the tube to be used with the socket, the upper face 55 of the base being provided with a recess 12 at

the upper end of the opening 11 to receive the annular bead formed around the mid-portion of the bodies of thermionic tubes of the acorn type. The upper end of the base 10 as illustrated in Fig. 1 is provided with holes 13 extending through it for mounting first connector clips on the base and similar holes 14 are provided through the lower end portion of the base for mounting second connector clips thereon. Additional holes 15 and 16 are provided through the side portions of the base and an additional hole 17 is provided through the lower portion of the base for any desired general purposes such as mounting the stage foundation, or making desired connections with the mounting plate or either of the capacitor plates employed, or any other purpose that may be desired in connection with the particular use to which the stage foundation is put. As shown in Figs. 2 and 3, each of the holes 13, 14, 15, 16 and 17 is provided in the back portion of the base 10 with an enlarged hexagonal recess, which recesses extend somewhat more than half way through the base, to receive threaded nuts when it is desired to mount contact lugs or other parts or apparatus on the base. In practice, I find it convenient to make the holes 15, 16 and 17 of a diameter to clear a No. 2 machine screw, the holes 13 and 14 being preferably sufficiently larger than the holes 15, 16 and 17, so that eyelets may be employed to secure the connector clips to the base 10, said eyelets having internal diameters sufficiently large to clear No. 2 machine screws for connection purposes. In addition to the holes described, the base is provided with flatsided openings 18 and 19 to receive lugs on the connector clips for the purpose of preventing angular movement of said clips when mounted on the base 10. The lower portion of the base 10 is also provided with an outstanding integral portion 20 centrally disposed laterally of the base to form a guard preventing the insertion of a tube in the socket in a position such that the tube prongs are oppositely disposed to what they should be to properly engage the connector clips mounted on the base 10.

The base illustrated in Figs. 1-3 inclusive, as well as the structures shown in Figs. 4-6 inclusive and 8-11 inclusive, are shown to a scale that is substantially twice the full size of the parts illustrated, which will clearly indicate the small size of the socket and of the stage foundation of which it is a part, the base 10 being made as narrow as the openings 11 and 12 and the necessary strength of the base will permit, and having a height which is greater than its width by only the requisite amount to properly secure the connector clips to the base.

In Fig. 4 I illustrate in plan view a base 10 having first connector clips 21, 22 and 23 mounted thereon by eyelets as described and also second connector clips 24 and 25 similarly mounted thereon. In this figure the socket thus formed is shown as secured to a grounded mounting plate 26 by screws 27, which mounting plate may be a part of a sheet metal chassis or any other metal mounting plate, to give stable support to the stage foundation. In this figure I also show a connector lug 28 secured to the base 10 by a screw 29, and I also show connecting screws 30, 31, 32 and 33 extending through the connector clips 21, 22, 24 and 25 respectively for purposes that will be described. In Figs. 5 and 6, I illustrate a construction of a capacitor plate 34 which is preferably of sheet metal of uniform thickness

of the same external size and shape as the base 10 and provided with a central opening 35 of the same size as the opening 11 in the base 10. The plate 34 is additionally provided with top openings 34a and 34b, in alignment with the openings 13 in the base 10, of which the opening 34a is a clearance opening of ample size to clear a No. 2 machine screw, and the openings 34b are threaded openings of proper size to engage connecting screws, for example No. 2 machine screws. In addition the plate 34 is provided with openings 34c and 34d through its lower portion in alignment with the openings 14 and 17 through the base 10, of which the openings 34c are clearance openings and the opening 34d is a threaded opening for engagement with a connecting screw. In addition, the plate 34 is provided with openings 34e and 34f through its left-hand side portion as illustrated, for alignment with the openings 15 through the base, of which the opening 34e is a clearance opening and the opening 34f is a threaded opening for engaging a connecting screw. In addition, openings 34g are provided through the right-hand side portion of the plate 34 for alignment with the openings 16 through the base 10, both of the openings 34g being clearance openings.

One use of the stage foundation described is illustrated in connection with the schematic circuit drawing shown in Fig. 7 in which a pentode thermionic tube is illustrated, which is provided with a heater filament 36 connected with wires 37 and 38 extending to a suitable source of heater current, a cathode 39 connected with a resistor 40 in parallel with a by-pass capacitor having an active plate 34 and a grounded plate connected with the other terminal of the resistor 40, said cathode also being connected with the suppressor grid 41 of the tube; said tube also includes a control grid 42 connected with an input conductor 43, and a screen grid 44 connected with the active plate 45 of a by-pass capacitor, the other plate of which is grounded, the capacitor plate 45 also being connected with a conductor 46 for supplying proper voltage to the screen grid 44; in addition, the tube includes a plate 47 connected with an output conductor 48. Any suitable coupling devices may obviously be employed between the tube illustrated in Fig. 7 and the preceding and succeeding stages of the radio apparatus, which, as illustrated, may be part of a radio receiver.

The stage foundation illustrated in Fig. 4 is arranged to effect the hook-up illustrated in Fig. 7, and as a part of this particular stage arrangement, a capacitor plate 34 constructed and positioned as shown in Fig. 5 is disposed between the base 10 and the mounting plate 26, said plate being suitably insulated from the mounting plate, and in addition a second capacitor plate 45 positioned as shown in Fig. 8 is mounted below the mounting plate 26 and insulated therefrom, in line with the base 10, and the capacitor plate 34, the plate 45 being identical in construction with the plate 34, the only difference being its angular disposition relatively to the plate 34, for as will be observed, the plate 45 is turned 180° from the position illustrated for the plate 34. For the construction of stage foundation described, and referring to Figs. 9, 10 and 11, it will be observed that the connector clip 24 is electrically connected by the screw 32 with the capacitor plate 45, and that the connector clip 21 is electrically connected by the screw 30 with the mounting plate 26. The clip 24 is the one making connection with the

screen grid in the thermionic tube, as a result of which the screw 32 effects the connection illustrated in Fig. 7 between the screen grid 44 and the active plate 45 of the corresponding by-pass capacitor. It will also be observed that the clip 21 is connected with one of the heater prongs of the tube, as a result of which the screw 30 makes electrical connection between the heater and the mounting plate 26, or in other words grounds the heater circuit as illustrated in Fig. 7. In Fig. 10 the screw 27 is shown as having threaded engagement with the mounting plate 26, but having no electrical connection with any other part of the circuit or apparatus, or in other words the screw 27 is one of the screws used to securely hold the stage foundation in place on the mounting plate 26, without serving any other function. The screw 31 extends through the clip 22, which is the clip for connection with the cathode of the tube and by having threaded engagement with the capacitor plate 34, the result is that the cathode of the tube is electrically connected with the active plate 34 of the by-pass capacitor, the other plate of which is the mounting plate 26 which is grounded and therefore serves to ground the by-pass circuit around the resistor 40. As shown in Fig. 11 the clip 25 is connected by the screw 33 with the plate 34, and since the clip 25 is for connection with the suppressor grid prong of the tube, the suppressor grid is connected with the active plate 34 of the corresponding by-pass capacitor as required by Fig. 7. As shown in Fig. 11, the screw 29 connects a connector lug 28 with the capacitor plate 45, thereby making an electrical connection between the screen grid 44 and the connector lug 28 to facilitate the connection of the wire 46 with the screen grid of the tube.

It will be noted that each of the capacitor plates 34 and 45 has two working positions relatively to the base 10, when facing the observer as shown in Figs. 5 and 8, and that it has two additional positions when turned over to its reverse position, thus affording four positions of use for each of said plates for any one position of use of the other of said plates, which provides for many possible set-ups of the circuit wiring, without making any structural changes whatever in the capacitor plates, the disposition of the clearance and threaded openings through the plates described in connection with Fig. 5, providing the necessary clearance passages around the connecting screws and the necessary threaded openings to be engaged by the connecting screws for said different set-ups. This results from the apertures 13, 14, 15, 16 and 17, considered collectively, being symmetrically disposed about the longitudinal and transverse center lines of the socket base 10, and the openings in the capacitor plates being similarly disposed. It will be understood of course that in any particular case, the mounting plate, which is the ground plate of the two capacitors, is provided with suitable clearance openings and threaded openings, as the case may be, to cooperate with the particular set-up employed, so that results may be secured in any case, in the manner illustrated in Figs. 9-11 inclusive.

Each of the connector clips employed on the socket for separable engagement with the radial prongs of the tubes, is preferably constructed as shown in Figs. 12-15 inclusive, for the connector clip 21. The clip illustrated is made from thin spring sheet metal, for example phosphor bronze, and includes a flat base portion having an opening 21a to receive the eyelet or other fastening

device used to secure the clip to the base 10 of the socket. At one end of the base of the clip, the material thereof is bent at substantially right angles to form an outstanding terminal lug 21b. At the clip portion which is nearest the opening 11 in the base 10, the material is a relatively narrow strip folded as illustrated at 21c, so that, as more clearly shown in Fig. 15, the outer part of said folded portion is spaced above and substantially parallel with the base or floor of the clip, to leave ample room for an inturned end portion 21d which extends between the base or floor of the clip and the outermost part of the folded portion 21c, the inner end of the part 21d being near but spaced from the vertical end wall 21e of the folded portion 21c which supports said folded portion from the base of the clip. The base of the clip at its edge remote from the wall 21e of the folded portion, is provided with a downwardly projecting lug 21f for engagement with one of the openings 18 or 19, depending on how the clip is mounted on the base of the socket, to restrain the connector clip from angular movement on the said base. The inner portion 21d of the folded portion 21c is spaced from the floor of the clip at such a distance that the entry of one of the radial prongs of the tube to be used with the stage foundation, will force the folded portion 21c upwardly away from the floor of the clip, as shown in Fig. 16, which represents the entry position of a prong 47 between the floor of the clip and the lower part 21d of the folded portion of the clip. This results in raising the entire folded portion of the clip when the prong is entered under the folded portion thereof, and continued rotation of the tube moves the prong 47 until it reaches its normal terminal position indicated in Fig. 17, at which time it rests against the wall 21e of the folded portion of the clip and under the inner end of the part 21d, thus relieving the outer part of the folded portion from the greater part of the lifting effort and correspondingly raising the inner end of the portion 21d so that the inclined condition thereof relatively to the floor of the clip, will tend to hold the prong 47 in the position indicated in Fig. 17. It will readily be observed that the length of the folded portion 21c angularly around the opening 11, accommodates any substantial lack of regularity of the prongs of the tubes angularly, resulting from variance in tube manufacture, since for any position of the prong between its entry position indicated in Fig. 16 and its normal position of engagement indicated in Fig. 17, the prong will be positively engaged by the connector clip, and in a manner in each case to make good electrical connection between the prong and the floor of the connector clip.

By referring to Fig. 12, it will be noted that the folded portion 21c is substantially spaced from the terminal lug 21b, and also that the lug 21f is narrower than the folded portion 21c, said lug being in line with said folded portion at its lower edge. This spacing of the folded portion is made use of by providing the floor of the clip with a substantially cut-out part at 21g and a second cut-out portion at 21h, forming a neck 21i between said cut-out portions, which is of sufficiently reduced width to constitute a flexible connection between the body portion of the clip and the folded portion 21c. In Fig. 18 a condition is illustrated in which a prong 47a of the tube used with the socket, is lower than the other prongs, so that the folded portion 21c of the clip 21 is depressed below its normal position, which is permitted by mount-

ing the clip 21 in each case on a thin washer 48, in securing the clip to the base 10 of the socket. For this position of the parts, the folded portion 21c of the clip will be separated somewhat more from its base portion than if the prong 47a were in normal position vertically, but this is readily taken care of by the construction of the folded portion of the clip, and in any event the prong 47a is in good electrical contact at its tip with the floor of the clip, as a result of being pressed firmly downward by the lower, outer edge portion of the part 21d of the clip. On the other hand, where a tube prong 47b is above its normal position as illustrated in Fig. 19, the folded portion 21c of the clip is raised above the position illustrated in Fig. 13, but for this condition of the parts, the outer edge portion of the floor of the clip is still in good electrical contact with the prong 47b because of being held firmly in engagement therewith by the pressure of the folded portion 21d downwardly on the end of the prong, so that in any case the electrical path from the prong to the central mounting portion of the clip 21 is through the floor of the clip and for substantially the same distance, thus eliminating possible changes in inductive effect which might otherwise result from changed paths of flow of the current for different conditions of contact between the tube prongs and the contact portions of the connector clips. Positive contact between a tube prong and a contact clip described, is preferably insured by providing a cutting edge 21k on the outer edge portion of the part 21d and extending towards the floor of the clip, which edge is effective where the tube prong is oxidized, as is frequently the case, in cutting or breaking through the oxide coating and making good electrical contact with the metal of the tube prong.

In Fig. 10 a tube of the acorn type is illustrated in place in the stage foundation at 49, to show the relation between the radial prongs 49a and the connector clips of the stage foundation.

It will be noted that the prongs of acorn tubes are usually symmetrically disposed relatively to a vertical axis when a tube is in place engaging the contact clips illustrated in Fig. 4, as a result of which, from the construction described, the tube may be connected with the contact clips by inserting either end of the tube into the aperture 11 in the base 10, the contact clips, of course, being correspondingly electrically connected in the hook-up used, which is an advantage in some cases.

From the above it will be seen that my invention provides an improved stage foundation construction which mounts the essential parts of a radio stage in exceedingly small compass and without the use of connecting wiring, with all of the advantages incident to a self-contained structure in which all of the parts are held in fixed position relatively to each other, and furthermore that the capacitor plates constructed as described are a novel part of the invention and may be used for many purposes other than those above described. It will also be understood that the socket construction described, as well as the novel form of connector clips illustrated, are susceptible of many uses and are an important part of the invention disclosed whether constituting a part of the stage foundation construction described or not.

While I have shown my invention in the particular embodiments above described, I do not limit myself thereto as I may employ equivalents thereof without departing from the scope of the appended claims.

Having thus described my invention, what I claim is:

1. A socket for use at ultra-high frequencies for tubes having radial connector prongs, including in combination a mounting plate and a plurality of clip constructions, each of said clip constructions having a prong-engaging portion for engaging a tube prong by rotary movement of the tube and having also a mounting portion for attaching the clip construction to said mounting plate, each of said prong-engaging portions being spaced from said mounting plate and the connection between each of said prong-engaging portions and the corresponding mounting portion being rigid in the direction of movement of the tube prong into engagement with the prong-engaging portion and flexible in the direction axially of the rotary movement to enable said prong-engaging portions to accommodate irregularities axially in the position of the tube prongs.
2. A socket for use at ultra-high frequencies for tubes having radial connector prongs, including in combination a mounting plate and a plurality of clip constructions, each of said clip constructions having a prong-engaging portion for engaging a tube prong by rotary movement of the tube and having also a mounting portion for attaching the clip construction to said mounting plate, each of said prong-engaging portions being spaced from said mounting plate and the connection between each of said prong-engaging portions and the corresponding mounting portion being integral therewith and of reduced width to render said connection flexible in the direction axially of the rotary movement.
3. A socket for use at ultra-high frequencies for tubes having radial connector prongs, including in combination a mounting plate and a plurality of clip constructions, each of said clip constructions having a prong-engaging portion for engaging a tube prong by rotary movement of the tube and having also a mounting portion for attaching the clip construction to said mounting plate, each of said prong-engaging portions being provided with a cutting edge and being spaced from said mounting plate and the connection between each of said prong-engaging portions and the corresponding mounting portion being integral therewith and of reduced width to render said connection flexible in the direction axially of the rotary movement.
4. A socket for use at ultra-high frequencies for tubes having radial connector prongs, including in combination a mounting plate and a plurality of clip constructions, each of said clip constructions having a prong-engaging portion for engaging a tube prong by rotary movement of the tube and having also a mounting portion for attaching the clip construction to said mounting plate, each of said prong-engaging portions being spaced from said mounting plate and the connection between each of said prong-engaging portions and the corresponding mounting portion being integral therewith and of reduced width to render said connection flexible in the direction axially of the rotary movement, each of said clip constructions having an extension protruding in the direction axially of the rotary movement and engaging said plate and

restraining said clip construction from rotational displacement.

5. A socket for use at ultra-high frequencies for tubes having radial connector prongs, including in combination a flat mounting plate and a plurality of clip constructions, each of said clip constructions being an integral structure of sheet metal and having a prong-engaging portion for engaging a tube prong by rotary movement of the tube and having also a mounting portion and an intermediate portion connecting said prong engaging portion and said mounting portion, each of said prong-engaging portions being relatively free to move axially of

said rotary movement, the base of said prong-engaging portion being in contact with the corresponding tube prong for any operative position of the tube, and said base, said intermediate portion and said mounting portion being in a single plane adjacent to and substantially parallel with said mounting plate, each of said intermediate portions being rigid in the direction of said rotary movement and relatively flexible axially of said rotary movement to enable said prong-engaging portions to accommodate irregularities in the position of the tube prongs axially of said rotary movement.

DWIGHT V. SINNINGER.
